FIG. 3

FIG. 4

Inventor:
James Hall Taylor
By Fred Gerlach
his Atty.

UNITED STATES PATENT OFFICE.

JAMES HALL TAYLOR, OF OAK PARK, ILLINOIS.

STEAM BOILER.

Application filed March 17, 1924. Serial No. 699,622.

The invention relates to steam boilers and more particularly to the internally fired type, in which the combustion-chamber is formed of metal which is independent of, 5 or supported without being stayed to, the boiler head or walls, so that the chamber and boiler walls may expand and contract independently, responsively to differential temperature conditions or pressures in the 10 water chamber and the combustion chamber.

The object of the invention is to provide an improved construction for combustion chambers of this type which will eliminate the stay bolts between the combustion chamber 15 and boiler head, and which will efficiently endure the stresses incident to sharp differential variations in internal and external pressures without fracture or other injurious effect.

20 The invention consists in the several novel features hereinafter set forth and more particularly defined by claims at the conclusion hereof.

In the drawings: Fig. 1 is a vertical longitudinal section of a boiler embodying the 25 invention. Fig. 2 is an end view of the combustion chamber, the boiler wall being shown in section. Fig. 3 is a section taken on line 3—3 of Fig. 1. Fig. 4 is a section 30 on line 4—4 of Fig. 1.

The invention is exemplified in an internally heated boiler comprising a cylindrical wall or body 4 supported by an outwardly bulged head 5 riveted or secured in any suitable manner to one end of the wall 4 and forming the back of the boiler, a head 7 which may be bulged outwardly as shown in Fig. 1, and which is secured in any manner, as head 5, to the other end of wall 4 40 and forming the boiler-front, a furnace 8 formed of a hollow pipe, a combustion-chamber formed of an outer head 10 and an inner head 11, flues 13 between the combustion-chamber, head 11 and the front-wall 45 7, and a stack 14 for the products of combustion, into which the flues discharge and which is connected to front wall 7. The furnace 8 may be heated by a grate 9 of the usual construction as shown in Fig. 1, or 50 may be allowed to receive the products of combustion from an oil burner, Dutch oven, or any other suitable heat producing means.

The combustion-chamber is independent 55 of or unattached to the boiler-walls, being supported therefrom so as to permit rela-

tive or differential contraction and expansion of the combustion-chamber and walls responsive to differential contraction and expansion, resulting from variations in the 60 temperature, by loosely interfitting lugs 15 and 16, which are secured respectively to the outer sides of the combustion-chamber and the inside of the wall 4 of the boiler. The boiler walls, stack, flues and furnace 65 may be of any suitable construction, and the boiler is provided with the usual inlet for water 20, outlet for steam 21, manhole 22 for access to the inside of the boiler, and drain 25 for withdrawal of the water and 70 sediment from the boiler, as well understood in the art.

When the combustion-chamber is not stayed to the boiler walls, it must be constructed so as to withstand marked variations of differential internal and external pressure, and for this purpose the heads 10 and 11 are dished or bulged outwardly and have their lapped margins riveted or otherwise secured together at 17, and the outer contour of the combustion-chamber is circular with a chordal top 18. The heads 10 and 11 are formed of boiler-plate and the head 10 is integrally deformed to render it 80 more efficient in withstanding differential external and internal pressures. The deformations of head 10 consist of transversely fluted or corrugated portions 10^a and longitudinally extending corrugations 23 in the top or chordal portion of the combustion-chamber. These corrugations make it possible for the wall of the combustion-chamber to resist external pressure and to expand and contract responsively to marked differences or variations in temperatures in the 85 combustion and water chambers.

The invention exemplifies an internally heated type of boiler in which the combustion-chamber is independent of the boiler-wall to permit differential expansion and contraction, is formed of boiler-plate, 100 is shaped to efficiently prevent fracture or other injury as the result of widely different internal and external pressures, to which in practice the chamber is usually subjected under working conditions, is re-inforced by integral deformation of the heads thereof and can be produced at a comparatively low cost.

The invention is not to be understood as 110 restricted to the details set forth, since these may be modified within the scope of the ap-

pended claims, without departing from the spirit and scope of the invention.

Having thus described the invention, what I claim as new and desire to secure by Letters Patent, is:

1. In a boiler, the combination of walls forming an outer shell, a furnace disposed inside the shell, a combustion chamber formed independently of said walls and having front and rear outwardly and spherically bulged walls marginally united, the furnace being joined to one of the walls of the combustion chamber, and flues leading from the chamber.
2. In a boiler, the combination of walls forming an outer shell, a furnace disposed inside the shell, a combustion chamber formed independently of said walls and having front and rear outwardly and spherically bulged walls having annular and chordal united margins, the furnace being joined to one of the walls of said combustion chamber, and flues leading from the chamber.
3. In a boiler, the combination of an outer shell, a furnace disposed inside the shell, a combustion chamber formed independently of the shell and composed of front and rear walls, one of said walls being fluted or corrugated transversely to reinforce it against the stresses of external and internal pressures, the furnace being joined to one of said walls, and flues leading from the chamber.
4. In a boiler, the combination of an outer shell, a furnace disposed inside of the shell, a combustion chamber formed independently of the shell and having front and rear outwardly and spherically bulged walls, one of

said walls being integrally and transversely deformed to reinforce it against the stresses of internal and external pressures, the furnace being joined to one of said walls, and flues leading from the chamber.

5. In a boiler, the combination of an outer shell, a furnace disposed inside the shell, a combustion chamber formed independently of the shell and having front and rear walls having annular and chordal united margins, one of said walls being integrally and transversely deformed to reinforce it against the stresses of internal and external pressures, the furnace being joined to one of said walls, and flues leading from the chamber.

6. In a boiler, the combination of an outer shell, a furnace disposed inside the shell, a combustion chamber formed independently of the shell and having front and rear circular walls having chordal top portions, the chordal top portion of one of the walls being fluted or corrugated longitudinally of the furnace, the furnace being joined to one of the walls, and flues leading from the chamber.

7. In a boiler, the combination of an outer shell, a furnace disposed inside the shell, a combustion chamber formed independently of the shell and having front and rear circular walls having chordal top portions, one of said walls having transverse corrugations in its face and corrugations in its chordal top extending longitudinally of the furnace, the furnace being joined to the other wall, and flues leading from the chamber.

Signed at Chicago, Illinois, this 28th day of February, 1924.

JAMES HALL TAYLOR.
